UNITED STATES PATENT OFFICE.

ARTHUR F. HOLMES, OF FAIRPORT, NEW YORK.

BEAD-SHAPING TOOL.

Application filed May 9, 1925. Serial No. 29,163.

This invention relates to an improved tinner's bead-shaping tool, and seeks, among other objects, to provide a tool especially adapted for opening the flattened end of the 5 bead of an eaves trough or the like and shaping the end of the bead to its natural contour.

The invention seeks, as a further object, to provide a tool which will eliminate the 10 hazard heretofore experienced in opening the end of a flattened eaves trough bead so that injury to the operator will be precluded.

Still another object is to provide a tool which may be readily forced into the flattened 15 end of a bead and then operated with facility for shaping the bead.

And the invention seeks, as a still further object, to provide a tool which will be of simple construction, sturdy and efficient.

20 Other and incidental objects will appear hereinafter.

In the accompanying drawings:

Figure 1 is a perspective view showing my improved tool in connection with a conventional eaves trough.

Figure 2 is a plan view of the tool.

Figure 3 is a detail sectional view on the line 3—3 of Figure 2, looking in the direction indicated by the arrows.

30 In carrying the invention into effect, I employ a pair of crossed levers 10 and 11 pivotally connected by a bolt or other fastening device, while each of said levers is formed with an angularly disposed forward end portion 12, which end portions lie substantially parallel when the jaws of the levers are closed. Formed on the portion 12 of the lever 10 is an axially aligned cylindrical 35

jaw 13 having a tapered nose 14 which is thus reduced in size and, as best shown in Figures 1 and 2, said nose is formed with flat side faces 15 substantially parallel to the flat side faces of the lever. The nose is thus substantially wedge-shaped, but is, nevertheless, provided with rounded upper and lower edges. Formed on the portion 12 of the lever 11 is a semi-cylindrical jaw 16 40

adapted to overlie the jaw 13 seating flat thereagainst. The jaw 16 is of a length to extend from the rear end of the jaw 13 to the base of the nose 14 of the latter jaw so that the jaw 13 thus projects beyond the forward end of the jaw 16 and, as shown in Figure 1, the portion 12 of the lever 11 is continued along the back of the jaw 16 to 45

form a reinforcing rib 17 therefor.

In Figures 1 and 3 of the drawings, I have shown the manner in which the tool is used. A length of conventional eaves trough is indicated at 18 and the cylindrical bead 60 thereof at 19. In any instance where it becomes necessary to cut off an end of a length of trough, the bead is unavoidably flattened at its adjacent end. Accordingly, before another length of trough can be properly soldered to the severed end of the former length, it becomes necessary to open and reshape the flattened end of the bead in order that one end of the second length of trough 65 may properly mate with the adjacent end of 70 the first length mentioned. Heretofore, it has been customary to employ a screw driver, cold chisel or the like for opening and reshaping the flattened end of such a bead. However, such tools have not only 75 proven inefficient and unhandy, but injury to the operator has often been caused by the sudden opening of the bead, with the result that the hand of the operator, in plunging forward, has been cut against the sharp 80 edges of the bead and trough. The present invention has, therefore, been devised with a view of overcoming these disadvantages.

Initially, the lever 10 is grasped and the nose 14 of the jaw 13 inserted into the flattened end of the bead, and, in this connection, it is to be observed that, in cutting a length of trough, the bead is, as shown in Figure 1, always flattened in such manner that the free inner margin of the bead lies 85 substantially parallel to the adjacent side of the trough. In other words, the bead is elongated against the adjacent side of the trough. Accordingly, when inserting the nose 14 in the bead, the flat faces 15 of said 90 nose are presented to the sides of the flattened end of the bead. The nose will, therefore, be guided into the bead by said faces while the tool will be located by said faces 95 in such manner that the jaw 16 will be disposed over the upper side of the bead.

Having initially inserted the nose 14 of the jaw 13, the lever 10 is pushed forwardly for forcing the jaw into the bead and since the lever 11 crosses the lever 10, the latter 105 lever will, should the bead suddenly open to permit the jaw to plunge forwardly, engage the end of the trough for limiting the lever 10 in its forward movement and thus preventing the hand of the operator from being 110 injured against the end of the trough. As the jaw 13 is forced into the bead, as indi-

cated, the flattened end of the bead will, of course, be opened by said jaw so that the lever 11 may then be grasped for swinging the jaw 16 downwardly against the bead, 5 when, by rotating the jaws with respect to the bead and compressing the bead therebetween, the flattened end of the bead may, as shown in Figure 3, be readily reshaped 10 to its natural cylindrical contour. As will be perceived, the tool may be operated with one hand of the operator to accomplish the entire reshaping operation of the bead, so that should the trough be suspended in place at the eaves of a roof, the other hand 15 of the operator will be free to grasp a ladder. Accidents, such as might otherwise occur, will accordingly be avoided.

Having thus described the invention, what I claim is:

- 20 1. A shaping tool for the bead of an eaves trough including coacting pivotally connected levers one having a jaw shaped to conform to the natural shape of the bead and insertable therein and the other having a mating jaw to overlie the bead for shaping the bead between the jaws, the former jaw projecting beyond the forward end of the latter jaw.
- 25 2. A bead shaping tool including crossed pivotally connected levers one provided at its forward end with a jaw having an entering nose of reduced size and the other pro-

vided with a mating jaw to coact with the former jaw and terminating at its forward end adjacent the base end of said nose.

35

3. A bead shaping tool including crossed pivotally connected levers one having a cylindrical jaw terminating in a tapered entering nose and the other having a coacting trough-shaped jaw to fit the cylindrical portion of the former jaw and terminating at its forward end adjacent the base end of said nose.

40

4. A bead shaping tool including crossed pivotally connected levers one having a cylindrical jaw terminating in a tapered wedge-shaped entering nose and the other having a coacting trough-shaped jaw to fit the former jaw and terminating at its forward end adjacent the base end of said nose.

45

5. In a bead shaping tool, the combination of coacting pivotally connected levers, a substantially cylindrical jaw carried by one of said levers and provided at its forward end with a tapered portion having flat 55 side faces to define a wedge shaped entering nose, and a coacting trough-shaped jaw carried by the other of said levers to fit said first mentioned jaw and terminating at its forward end near the base of said nose.

60

In testimony whereof, I affix my signature.

ARTHUR F. HOLMES. [L.S.]
